UNITED STATES PATENT OFFICE.

MICHAEL McCARTHY, OF BOSTON, MASSACHUSETTS.

LETTER-CARRIER'S BAG.

SPECIFICATION forming part of Letters Patent No. 633,884, dated September 26, 1899.

Application filed January 18, 1899. Serial No. 702,501. (No modsl.)

To all whom it may concern:

Be it known that I, MICHAEL McCARTHY, of Boston, (Roxbury,) in the county of Suffolk and State of Massachusetts, have invented a new and Improved Letter-Carrier's Bag, of which the following is a full, clear, and exact description.

The purpose of this invention is to provide a means by which letter-carriers may stow in their boxes or satchels the letters of their routes in such a way that the letters may be readily taken out in the order of the route and to avoid the use of twine in tying up the bundles of letters, as is generally done, and also to save time in the delivery of the mail.

To this end I provide the usual letter-carrier's bag or satchel with a box or holder fitted in one end of the bag and having flaps at its front side, which may be connected or disconnected to permit placing and displacing the letters which are to be stacked in the box or holder.

This specification is the disclosure of one form of my invention, while the claims define the actual scope thereof.

Reference is to be had to the accompanying drawings, forming a part of this specification, in which similar characters of reference indicate corresponding parts in all the views.

Figure 1 is a perspective view of my invention. Fig. 2 is a sectional view taken horizontally on the line 2 2 of Fig. 1. Fig. 3 is a sectional view taken vertically on the line 3 3 of Fig. 1, and Fig. 4 is a perspective view of a modified form of the invention.

Figs. 1, 2, and 3 show the invention applied to an ordinary letter-carrier's bag, in doing which one end of the bag is removed and a box or holder is set into the same and secured by lines of stitching *a*. The holder is rectangular in form, so that the letters *b* (see Fig. 3) may be superimposed therein. The outer or front wall of the holder is formed of two flaps *c*, which are provided with reusable fastening devices *d*, running throughout the vertical extent of the box or holder and providing means by which the front wall may be entirely closed or opened one fastener at a time, so that the letter-carrier may conveniently reach the letters as the stack in the box or holder diminishes in height. The flap *e* of the bag partly covers the box or

holder, and the other part of the box may be left uncovered or provided with a hood for its closure, as desired.

The letters of the carrier's route should be packed in the box or holder, as shown in Fig. 3, so that the first letter of the route will be on top and the others in the proper succession, thus enabling the carrier to readily take the letters from the bag. The other part of the bag may be made to carry newspapers and other bulky matter.

The construction shown in Fig. 4 is adapted as a means for carrying letters which cannot be stowed in the box when attached to the bag—that is to say, should the letter-carrier have some letters that cannot be placed in the box of the bag he may put these additional letters in the device shown in Fig. 4. This consists in a bag of a form essentially the same as that shown in the first three figures and having the flaps *c* joined by fastening devices *d*. This box may be covered by a hood *f* and provided with a strap *g* for slinging it over the shoulder of the letter-carrier.

Having thus described my invention, I claim as new and desire to secure by Letters Patent—

1. A mail-carrier, consisting in a vertically-elongated box or holder open at the top and having an angular cross-section, the box being adapted to have the letters superimposed therein so that the letters may be taken out from the top of the box or holder, one wall of the box or holder being formed of vertically-extending flaps, and fastening devices carried on the adjacent edges of the flaps to secure the flaps together, such fastening devices being independently operative so that the flaps may be opened at any point along the length of the box.

2. A letter-carrier's bag, having a bag proper provided with a flap forming the cover of the bag proper, a box or holder, the upper end of which is open, the box or holder being secured in one end of the bag proper, to form the end wall thereof, and the box or holder being partly covered by the flap of the bag, the outer wall of the box or holder being formed of two vertically-extending flaps, and fastening devices on the contiguous edges of the flaps to join the flaps to each other, the

fastening devices being independently operative to permit opening the box or holder at any point along its length.

3. A letter-carrier's bag, having a bag proper, a flap at the top of the bag proper and forming the closure thereof, and a box or holder secured in one end of the bag proper and forming the end wall thereof, the box or

holder having an open upper end partly closed by the said flap, and being capable of carrying letters superimposed in the box or holder.

MICHAEL McCARTHY.
